REEL STRUCTURE

Clarence J. Klein, Steubenville, Ohio

Application October 26, 1936, Serial No. 107,515

20 Claims. (Cl. 242—72)

My invention relates broadly to reel structures and is particularly applicable to an improved collapsible reeling apparatus adapted for the effective coiling of strip material. Inasmuch as my invention is peculiarly suitable for use in connection with strip rolling mills, it will be described as a structure useful for coiling strip metal, but it is to be understood that it may be satisfactorily employed for coiling other sheet or strip material.

In the metal strip rolling art, it is customary to deliver strip material from the last or finishing stand of the rolling mill directly to reeling or coiling mechanism by means of which the material is formed into coils for ease in subsequent handling and to reduce the operating space requirements of the mill. Due to the great weight of coils which are now being produced and the heavy tension on the material exerted by the reel, it is essential that the reel should be as rigidly constructed as possible so as to minimize distortion in order that the tension be evenly distributed over the strip as it leaves the last roll stand. This requires that the diameter of the central supporting shaft be as large as possible in comparison with the diameter of the reel. It is also highly desirable that the structure be as simple as possible so that the minimum of time will be consumed when assembling or disassembling the reel.

Furthermore, it is necessary that the reel be of the collapsible type to permit the release and removal of the finished coil of material, and the reel should be of such construction that it may be positively and readily expanded and contracted by the operator and present when in the winding or expanded condition, a winding surface of substantially continuous contour so that the finished material will not be marked.

My invention provides a collapsible reel of improved construction which is of great rigidity due to the large diameter of the supporting shaft in comparison to the diameter of the winding drum. The reel is positive in operation and of such simple construction that it may be assembled and disassembled in a comparatively short time and economically fabricated. Furthermore, the strip is uniformly coiled so as to preserve the finished characteristics of the material as it leaves the mill.

In the accompanying drawings, I have shown for purposes of illustration only, a preferred embodiment of my invention. In the drawings:

Figure 1 is a longitudinal partial section of one form of reel embodying the invention taken along

the line I—I of Figure 8, but on a smaller scale; Figure 2 is a view showing the joints between adjoining segments;

Figure 3 is a cross sectional view along the line III—III of Figure 6, but to a reduced scale; 5

Figure 4 is a cross sectional view along the line IV—IV of Figure 1, but to an enlarged scale;

Figure 5 is a cross sectional view along the line V—V of Figure 1, but to an enlarged scale;

Figure 6 is a cross sectional view along the line 10 VI—VI of Figure 1, but to an enlarged scale, showing the reel in the fully expanded condition ready for coiling the strip material;

Figure 7 is a view similar to Figure 6, but showing the reel in collapsed condition; 15

Figure 8 is a cross sectional view along the line VIII—VIII of Figure 1, but to an enlarged scale;

Figure 9 is a view of the right-hand end of 20 Figure 1, but to an enlarged scale;

Figure 10 is a detail view of the connection between the reel ends and the segments.

As illustrated in the drawings, the reel comprises a central shaft 2, which, as will be observed, is comparatively large in diameter in 25 comparison with the outside diameter of the reel and thereby forms a stiff structure. The shaft is supported at one end 3 and driven from that end by the usual means, such as an electric motor, not here shown. Rotatably mounted on 30

and concentric with shaft 2 is a sleeve or roller cage 4 having a number of discontinuous circumferential slots 5, into which is received the head of cap screws 6, which screws are secured to shaft 2. The slots are of the size and shape to allow 35

limited circumferential or rotary movement of the sleeve 4 about the shaft 2, but no appreciable longitudinal movement (see Figures 1, 3, 6, and 7). Formed in the sleeve is a plurality of longitudinally extending slots 7, three rows of six 40

each being shown (see Figures 3, 6, and 7). In slots 7, rollers 8 are received. Surrounding and spaced from sleeve 4 is a plurality of annular segments 9, three being shown. These segments form an expansible drum and present, when the 45

reel is in the expanded position shown in Figure 6, a circular coiling surface, the edges of the segments which abut one another being formed with interfitting portions 9a and 9b (see Figure 2) so that there is no continuous dividing line between 50

the adjoining segments. This prevents marking of the strip while being wound on the drum.

Received in appropriate longitudinal slots 2a in

the shaft 2 is a plurality of angularly disposed

cams or roller surfaces or races 10, two being 55

shown for each of the drum segments 9. The roller surfaces or races are preferably formed of hard material and are suitably secured as for example by screws 11. The outside corners of 5 the races are ground cylindrically with and to the same diameter as the shaft 2.

A plurality of roller surfaces or cams 13, two rows of which are shown in each segment, are secured by screws 14 in suitable slots on the inside 10 of the segments 9 (see Figures 6 and 7). The outside of these roller surfaces, which are preferably formed from hardened material, are concentric with the shaft 2 when the reel is in the expanded position. Received between each set 15 of roller surfaces 10 and 13 are the rollers 8 which have hardened surfaces. The roller surfaces 10 and 13, the slots 7 in sleeve 4 and the rollers 8 are so disposed that when the reel is collapsed, as shown in Figure 7, the various parts 20 are in the relation shown in which the surfaces of the cams are angularly disposed with reference to each other. If the shaft is then rotated anti-clockwise relative to the segments, or the segments rotated clockwise relative to the shaft, or 25 a combination of both movements is made, the various parts assume the position shown in Figure 6 which shows the reel fully expanded. In this position, the segments 9 are pushed outwardly by the rollers 8 which now engage the outer end 30 of the roller surfaces 10 and the roller surfaces 13.

It will also be observed that the rollers 8 are located in the neighborhood of the quarter points of the segments when the drum is expanded, so that deflection of the segments under load will be 35 at a minimum.

Adjacent the supported end 3 of shaft 2 and surrounding the shaft is a driving collar 16. The shaft 2 has a plurality of projecting lugs 17 which are received in keyways 18 in the inner surface of 40 the collar. The keyways 18 are of such circumferential size as to allow a certain amount of relative movement between the lugs 17 on shaft 2 and the collar 16. A retaining collar 19, mounted or formed integrally with shaft 2, 45 prevents longitudinal movement of the driving collar 16 toward the support. The side of the driving collar 16 facing the segments 9 of the winding expandible drum has a series of projecting lugs 20, one for each segment being shown, 50 which lugs are received into recesses 21 in segments 9. Wear plates 22 are secured to the sides and ends of recesses 21 and provide a smooth surface necessary for sliding movement between the segments 9 and the driving collar 16. Each 55 lug 20 has a hole 23 formed therein, into which is received a spring 24, one end of the spring abutting the bottom 25 of recess 21 of segment 9 and the other end abutting a threaded retaining member 26 received in hole 23 (see Figures 5, 8, and 10). By turning adjusting member 26, the tension of spring 24 may be varied. This spring when pressed tends to force the segments 9 inwardly and when the roller cage 4 is in the position shown in Figure 7, the segments 9 60 are positively forced into the position shown in Figure 7. Precisely the same arrangement is shown at the unsupported end of the reel, a section of which is shown in Figure 8, to which the same numerals have been applied with the suffix (') affixed thereto. The end driving collar 27 is supported on and driven by the unsupported end of the shaft 2 (see Figure 8). It will be observed 65 that the driving collar 27 has a driving connection with shaft 2 similar to the driving connection already described between driving collar 16 and

the shaft 2. A sealing member 28 is secured to the unsupported end of shaft 2 by bolts 29 and makes a close joint with the end of the driving collar 27. An annular plate 30 is secured to the driving collar 27 by bolt 31.

Extending between driving collar 16 and driving collar 27 are tie bolts 32. These tie bolts, three of which are shown, are located radially adjacent the abutting ends of the segments. These tie bolts have projections 33 and 34 intermediate the ends, which projections are received in suitable slots 35 and 36 in roller cage 4. The slots in the roller cage are wider than the projections of the tie bolts and are of such size that the edges will contact the edges of the slots in the 15 roller cages upon relative rotation between the driving collars 16 and 27 and the shaft 2 (Figures 6 and 8). This arrangement serves to loosen the cages in case they do not readily release when the shaft 2 is moved clockwise relative to the 20 segments 9 or the segments are moved anticlockwise relative to the shaft. These tie bolts also serve to move the driving collars 16 and 27 in unison and to hold the various parts of the reel in proper assembled relation.

At the beginning of operation, the reel is expanded by rotating shaft 2 anticlockwise, as shown in Figure 7, while the driving collar 16, and consequently collar 27, are held stationary by any suitable means such as a brake, not shown. 30 The movement of shaft 2 anticlockwise relative to the driving collars will cause the rollers 8 to ride along the roller surfaces 10 and 13 from the position shown in Figure 7 to the position shown in Figure 6. Due to the arrangement of the 35 roller surfaces 10 and 13, and under the influence of rollers 8, the segments 9 assume the position shown in Figure 6, which is the fully expanded position. The brake holding the driving collar is then released and the reel is ready to receive 40 the material to be wound thereon.

It will be observed that there is no means provided for holding the end of the strip in contact with the outer edge of the drum, and consequently, winding of the end of the strip around the 45 drum is accomplished by the use of the belt wrapping device of the type shown in the Menzer United States Patent No. 1,230,750. Inasmuch as the winding device forms no part of my invention, it is not considered necessary to further 50 describe it. It suffices to say that it is unnecessary to provide the customary gripping slot, although a gripping slot could readily be provided in an appropriate segment of the winding drum. After a few windings have been wrapped around 55 the drum, the material will be secured thereto in such fashion that no slippage will occur and the winding can be proceeded with.

It is, of course, understood that in expanding the reel, the shaft may remain stationary and 60 the driving collars to which the segments are attached may be rotated in a clockwise direction relative to the shaft, or a combination of both movements may be employed.

When the material has been wound to the desired extent on the reel, the reel is then collapsed in order that the formed coil may be removed therefrom. This collapsing is accomplished by allowing the reel to continue to turn in the winding direction while the shaft movement is retarded, or the reel may be stopped and the shaft rotated clockwise. The rollers 8 and cam surfaces 10 and 13 will assume the position shown in Figure 7 and the segments will be forced inwardly either by the weight of the coil thereon 75

or by the force of the coil springs 24 pressing against the lower end 25 of the recesses 21.

By such an arrangement as I have shown and described it is possible to design a winding reel so that the shaft is very rigid for a given reel diameter and of the largest diameter possible in comparison with the diameter of the winding drum and taking into account the necessary thickness of the segments. This is due to the fact that the expanding mechanism takes up but very little space and is simple and positive in operation. The mechanism is of very simple design and the reel can be readily assembled and disassembled in a very short time. All parts are readily accessible for replacement or repair, the reel is inexpensive to construct, and provides a very satisfactory winding surface.

It is, of course, understood that I have described a preferred embodiment of my invention as applied to a reel such as now in common use in the strip metal rolling industry, which reel is of the type which is supported only at one end thereof, the shaft acting as a cantilever beam. My invention can likewise be applied to a reel which is supported at both ends, in which case it is necessary to provide a bearing at what is now the unsupported end.

While I have herein illustrated and described a preferred embodiment of my invention, it will be understood that changes in the construction, operation and relationship of the parts may be made without departing from the spirit of my invention or the scope of my claims.

I claim:

1. In a reel, the combination of a supporting shaft, a plurality of movable segments disposed about said shaft and forming a winding drum, roller surfaces on the drum, roller surfaces on the shaft, said surfaces being angularly disposed with respect to one another, means between said surfaces for causing radial displacement of the segments with respect to the shaft upon relative rotation of the shaft and drum and means independent of the last mentioned means for transmitting rotary motion from the shaft to the drum and permitting only a limited arcuate movement between the shaft and the drum in either direction.

2. In a reel structure, an expandable drum, a supporting shaft, a driving collar on the shaft, a driving connection between said shaft and collar permitting only a limited arcuate movement between the shaft and the collar in either direction, a driving connection between said collar and the drum, drum-expanding means interposed between the shaft and the drum, and drum-contracting means interposed between the driving collar and the drum.

3. In a reel structure, a plurality of movable segments forming a winding drum, a supporting shaft, a driving collar at each end of said drum connecting the drum and the shaft and permitting only a limited arcuate movement between the shaft and the drum, expanding means between the shaft and the drum for urging the segments outwardly, and means on said collars for urging said segments inwardly.

4. In a reel structure, an expandable drum, a supporting shaft, a driving collar at each end of said drum connecting the drum and the shaft and permitting limited rotative movement between the collars and the shaft, cam surfaces on the drum, cam surfaces on the shaft, rollers between said surfaces, a roller cage for maintaining said rollers in spaced apart relation, and means con-

necting said driving collars, said connecting means having means thereon for causing rotation of the roller cage upon relative rotative movement between the shaft and collar.

5. In a reel structure, the combination of a supporting shaft, an expandable drum axially disposed about said shaft, roller surfaces on the drum, roller surfaces on the shaft, said surfaces being angularly disposed with respect to one another, rollers between said surfaces, a roller cage for causing limited rotative movement of said rollers and for maintaining said rollers in spaced apart relation, a driving collar at each end of said drum connecting the drum and the shaft, and tie bolts connecting said driving collars, said tie bolts having projections thereon for causing movement of the roller cage upon relative rotation between the shaft and the collars.

6. A reel structure comprising a supporting shaft and an expandable drum, the latter being concentrically arranged about the former, rollers between the drum and shaft, means effective upon limited relative rotation of the drum and shaft for effecting radial movement of the rollers for expanding and contracting the drum, and means permitting such limited relative rotation for transmitting rotary motion from the shaft to the drum.

7. A reel structure comprising a supporting shaft and an expandable drum, the latter being concentrically arranged about the former, rollers between the drum and shaft, means effective upon limited relative rotation of the drum and shaft for effecting radial movement of the rollers for expanding the drum, means yieldably resisting said expanding movement to cause the contraction of the drum upon movement of the rollers in a direction opposite to the expanding movement, and means permitting such limited relative rotation for transmitting rotary motion from the shaft to the drum.

8. A reel structure comprising a supporting shaft and an expandable drum having segments which move radially in and out with respect to the center of the shaft, the drum being concentrically arranged about the shaft, rollers between the drum and shaft, means effective upon limited relative rotation between the drum and shaft for effecting radial movement of the rollers for expanding the drum, means yieldably resisting said expanding movement to cause the contraction of the drum upon movement of the rollers in a direction opposite to the expanding movement and means permitting and restricting such limited relative rotation for transmitting rotary motion from the shaft to the drum.

9. A reel structure comprising a supporting shaft and an expandable drum, the drum being concentrically arranged about the shaft, rollers between the drum and the shaft, means effective upon relative rotation of the drum and the shaft for effecting arcuate movement of the rollers for expanding the drum, and means permitting and restricting such relative rotation for transmitting rotary motion from the shaft to the drum.

10. A reel for coiling steel under tension comprising a shaft, an expandable drum on the shaft comprised of radially movable segments, collars on the shaft at the ends of the drum keyed to the shaft through a lost motion connection and keyed to the segments so as to allow radial movement of the segments, the inner surface of the exterior of the shaft having cam surfaces which extend a short distance about its periphery, the interior of the drum having cooperating cam surfaces.

- faces, rollers between the cooperating cam surfaces, and means for retaining the rollers in position, said cam surfaces and rollers cooperating to move the segments of the drum in or out with 5 relative rotation between the shaft and collars.
11. A reel for coiling steel under tension comprising a shaft, an expandible drum on the shaft comprised of radially movable segments, collars on the shaft at the ends of the drum keyed to the 10 shaft through a lost motion connection and keyed to the segments so as to allow radial movement of the segments, and means connecting the collars for causing the collars to move synchronously.
12. A reel for coiling steel under tension comprising a shaft, an expandible drum on the shaft comprised of radially movable segments, collars on the shaft at the ends of the drum keyed to the shaft through a lost motion connection and keyed 15 to the segments so as to allow radial movement of the segments, and means connecting the collars for causing the collars to move synchronously, cam surfaces on the drum, cam surfaces on the shaft, rollers between said surfaces, a roller cage 20 for causing limited rotative movement of said rollers and for maintaining said rollers in spaced apart relation, whereby the segments are moved outwardly upon relative arcuate movement between the shaft and drum.
13. A reel for coiling steel under tension comprising a shaft, an expandible drum on the shaft comprised of radially movable segments, collars on the shaft at the ends of the drum keyed to the shaft through a lost motion connection and keyed 25 to the segments so as to allow radial movement of the segments, and means interposed between the collars and segments for urging the segments inwardly.
14. In a reel, a supporting shaft member, a plurality of radially movable segments disposed about said shaft and forming a winding drum member, means for transmitting rotary motion directly from the shaft to the drum segments and permitting only a limited arcuate movement 30 between the shaft and the drum in either direction, cam surfaces on the shaft, cam surfaces on the drum in opposed relation to those on the shaft, the cam surfaces on one member being angularly disposed with respect to the cam surfaces 35 on the other member, rollers between said members operatively engaging said cam surfaces, means for maintaining said rollers in spaced apart relation, and for insuring movement of the rollers relative to each surface upon relative rotation between the shaft and drum whereby all 40 parts of each of the segments are simultaneously forced radially outwardly as a unit with respect to the shaft and in a plane at right angles to the longitudinal axis of the shaft by relative movement in one direction between the shaft and the drum, and means for urging the drum segments inwardly.
15. In a reel structure, an expandible drum, a supporting shaft, a driving collar at each end of 45 said shaft directly connecting the drum and the shaft and connected to the shaft by a lost motion which permits limited rotative movement between the collars and the shaft but secured against longitudinal movement, cam surfaces on the drum, cam surfaces on the shaft, said surfaces being angularly disposed with respect to each other, rollers between said surfaces, a roller cage surrounding the shaft for maintaining said 50 rollers in spaced apart relation and for insuring positive movement of the rollers, and means for 55 causing rotation of the roller cage upon relative rotative movement between the shaft and collar.
16. In a reel structure, the combination of a supporting shaft, an expandible drum composed of movable segments concentrically disposed about said shaft, roller surfaces on the drum, roller surfaces on the shaft, said surfaces being angularly disposed with respect to one another, rollers between said surfaces, a roller cage surrounding the shaft for causing limited 60 rotative movement of said rollers and for maintaining said rollers in spaced apart relation, a driving collar surrounding the shaft and directly connecting the drum and the shaft and permitting limited arcuate movement between the shaft and the drum, said collar being secured to the shaft against longitudinal movement and serving to support the segments at the ends thereof for axial movement from and toward the shaft so that all points on the segments will move 65 to and from the center line of the shaft in substantially equal amounts and in planes transverse to the longitudinal axis of the shaft and means for causing positive rotary movement of the roller cage upon relative rotation between the shaft and the collar.
17. A reel structure comprising a supporting shaft and an expandible drum composed of radially movable segments, the drum being concentrically arranged about the shaft, rollers extending 70 between the drum and shaft, a cage surrounding the shaft and effective upon limited relative rotation of the drum and shaft for effecting movement of the rollers away from and toward the center of the structure for expanding and contracting the drum in such manner that the median line of the drum moves at right angles to the longitudinal axis of the shaft, means for moving the cage, and means permitting limited relative rotation between the shaft and drum for transmitting rotary motion from the shaft to the drum.
18. In a reel, the combination of a supporting shaft member, a plurality of radially movable segments disposed about said shaft and forming a winding drum member, means for transmitting rotary motion from the shaft to the periphery of the drum segments and permitting only a limited arcuate movement between the shaft and the drum in either direction, a cam surface on the shaft, a plurality of cam surfaces on each segment angularly disposed with respect to the surface of the segments, means between said surfaces and movable relative to each surface for causing radial displacement of the segments outwardly with respect to the shaft and so that any point on each segment will move in a plane at right angles to the longitudinal axis of the shaft, and in substantially the same amount relative to the shaft upon relative rotation between the shaft and drum in one direction, and means for urging the segments inwardly.
19. A reel comprising a central supporting shaft, a collar at each end of the shaft mounted against longitudinal movement with respect to the shaft but having a limited arcuate movement relative to the shaft, radially movable segments forming a drum and connected at each end to the collars so as to be slidable radially relative thereto and so that all points on the circumference of the movable segments will at all times be substantially equi-distant from the central line of the shaft, and means interposed between the movable segments and the shaft and surrounding the shaft and intermediate said collars

for controlling the radial position of the movable segments upon relative rotative movement between the shaft and the collars.

20. A reel comprising a central supporting shaft, a collar at each end of the shaft mounted against longitudinal movement with respect to the shaft but having a limited arcuate movement relative to the shaft, radially movable segments forming a drum and connected at each 5 end to the collars so as to be slidable radially relative thereto and so that all points on the cir-

cumference of the movable segments will at all times be substantially equi-distant from the central line of the shaft, means interposed between the movable segments and the shaft and surrounding the shaft and intermediate said collars 5 for controlling the radial position of the movable segments upon relative rotative movement between the shaft and the collars, and means between the collars and the segments for urging the segments inwardly.

10

CLARENCE J. KLEIN.
